UNITED STATES PATENT OFFICE

117,684

DESIGN FOR A BASEBOARD CAP STRIP OR SIMILAR ARTICLE

William L. Bonnell, Columbus, Ohio

Application March 11, 1939, Serial No. 83,510

Term of patent 14 years

To all whom it may concern:

Be it known that I, William L. Bonnell, a citizen of the United States, residing at Columbus, in the county of Franklin and State of Ohio, have invented a new, original, and ornamental Design for a Baseboard Cap Strip or Similar Article, of which the following is a specification, reference being had to the accompanying drawing, forming a part thereof.

Fig. 1 is a perspective view of a baseboard cap strip or similar article showing my new design; Fig. 2 is a transverse sectional view thereof.

I claim:

The ornamental design for a baseboard cap strip or similar article, as shown.

WILLIAM L. BONNELL.
